UNITED STATES PATENT OFFICE.

LINDSLEY SCHEPMOES, OF HASBROUCK HEIGHTS, NEW JERSEY, ASSIGNOR TO THE SAFETY CAR HEATING & LIGHTING CO., OF NEW YORK, N. Y., A CORPORATION OF NEW JERSEY.

DESIGN FOR A DECK-LAMP FIXTURE.

43,120.

Specification for Design.

Patented Oct. 8, 1912.

Application filed August 23, 1911. Serial No. 645,671. Term of patent 7 years.

To all whom it may concern:

Be it known that I, LINDSLEY SCHEPMOES, a citizen of the United States, residing at Hasbrouck Heights, county of Bergen, and State of New Jersey, have invented a new, original, and ornamental Design for Deck-Lamp Fixtures, of which the following is a specification.

The nature of my design is fully illustrated in the accompanying drawing, to which reference is made, and in which—

Figure 1 illustrates an elevation of the design; and Fig. 2 a bottom plan view thereof.

My design comprises a pendant having an upright, generally rectangular, prismatic lower portion surmounted by a dome provided with curved walls converging from the upper part of the lower portion and interrupted by projections above the faces of the prismatic lower portion, producing a dormer effect, having the contour and relative proportion of parts shown.

I claim:

The ornamental design for a deck lamp fixture as shown and described.

LINDSLEY SCHEPMOES.
